PIVOT CONSTRUCTION

John W. Page, Chicago, Ill., assignor to Page Engineering Company, a corporation of Illinois

Application December 5, 1940, Serial No. 368,701

4 Claims. (Cl. 308—141)

This invention relates to improvements in pivot construction and more especially to such construction particularly applicable for use in connection with excavating machinery, derricks and the like mounted on platforms. The invention is more particularly adapted for use in connection with such heavy machinery which is mobile. The invention may be used, for example, in connection with walking mechanism of any kind in which the supporting platform (upon which the machinery is rotatably mounted) is lifted from the ground in connection with moving the mechanism. Such walking mechanism, for example, is shown in my copending application Serial No. 84,205, filed June 8, 1936, and in my Patent 2,164,-120, issued June 27, 1939. In various forms of mechanism of this general type in which the machinery house or platform is pivotally mounted upon a base or tub, such base or tub is lifted from the ground at various times during the moving or walking of the device so that it hangs from the pivot.

The pivot construction, therefore, must be very heavy and rugged because apparatus of the kind here under consideration usually weighs several tons. When the machine is resting on the base the pivot also must take considerable lateral strain because of the thrusts imposed thereon by the digging apparatus. This is especially true where a drag-line bucket is used.

Among the features of my invention is the making of such pivot construction of simplified design but very rugged so as to withstand the strains imposed upon the same by digging and by the weight of the tub or platform when the latter is lifted from the ground.

Another feature of the invention is the making of such pivot construction to permit easy adjustment of the same and easy detachment of the pivot for replacement or repair purposes.

Other features and advantages of my invention will appear more fully as I proceed with my specification.

In that forms of device embodying the features of my invention shown in the accompanying drawings, Fig. 1 is a view in side elevation, partly in section; Fig. 2 is an enlarged sectional view of the pivot construction; Fig. 3 is a view taken as indicated by the line 3 of Fig. 2; Fig. 4 is a view taken as indicated by the line 4 of Fig. 2; Fig. 5 is a view taken as indicated by the line 5 of Fig. 2; and Fig. 6 is a view taken as indicated by the line 6 of Fig. 2.

As shown in the drawings, 10 indicates a base or tub resting on the ground 11 when the ma-

chine is digging. This base supports the machinery platform 12 which is rotatably mounted on the base in the usual manner by wheels 13 operating between the circular tracks 14 and 15. A machinery house 12d is ordinarily mounted on the platform 12.

The pivot construction between the base 10 and platform 12 to which this invention relates is more particularly shown in Figs. 2-6. This construction shows a concave bearing seat 16 carried by the platform 12 with an aperture 16a therethrough and a similar concave bearing seat 17, carried by the base 10, with an aperture 17a therethrough. 18 indicates a pivot pin extending through said apertures. On the upper end of the pivot pin is a nut 19 having a convex bearing surface 19a engaging the concave surface 16b on the bearing seat 16. 20 indicates a locking member for the nut 19 having a squared opening 20a engaging the reduced squared end 18a of the pin 18 to prevent rotation thereon. The locking member 20 is provided with a depending flange or skirt 20b provided with internal notches 20c engaging teeth 19b on the nut 19 to prevent relative rotation. It will be seen, therefore, that with the locking member in the position shown in Fig. 2, rotation of the nut 19 on the pin 18 is prevented.

The lower end of the pivot 18 carries another nut 21. 22 indicates a locking member for the lower nut having a convex bearing surface 22a engaging the concave surface 17b of the bearing seat 17. When the base is lifted from the ground, the locking member 22 is held in locking position by pressure of the bearing seat 17 against the nut 21. When in such locking position the nut 21 is held against rotation for the following reasons. 18b indicates teeth on the pivot pin 18 engaged by co-acting teeth on the locking member 22; and the latter with a depending flange or skirt 22b provided with teeth 22c engaging teeth 21a on the nut 21 so that when the locking member 22 is in the position shown in solid lines in Fig. 2 the nut 21 will be locked against rotation.

The base 10 is provided with an upwardly projecting sleeve 10a in which the pivot 18 is loosely fitted. On this sleeve is mounted a bearing 12a carried by the socket 12b depending from the platform 12. The bearing 12a is mounted for universal movement in the socket 12b; and said bearing is capable of vertical sliding movement and rotational movement on the sleeve 10a.

In Fig. 2 the parts are shown in the position they occupy when the base 10 is raised from the ground and hangs on the pivot. It will be seen

that the nut 19 can be unlocked by merely lifting the locking member 20 off the end of the pin or shaft 18. When thus unlocked the nut 19 can be loosened from the pin allowing the pin to be dropped. Assuming that the base 10 is suitably supported on the ground or by other means, such dropping of the pin 18 will move the lower end 21 away from the seat 17 giving space therebetween to permit the locking member 22 to be raised from the nut 21 so that the latter will be unlocked. The pivot pin 18 can then be unscrewed from the nut 21. The nut 21 is preferably held against rotation by being provided with a square flange 21b held against rotation by the members 10b in the base. Vertical movement of the nut 21 in the base, however, is permitted.

The nut 19 can be removed from the upper end of the pivot pin 18 by lifting the locking member 20 out of locking engagement when the nut and pivot 18 are permitted to have relative rotation.

The sleeve 10a is rigidly mounted on the base 10 so that lateral stresses imposed by the digging operation will be taken by this sleeve through the bearing 12a thereon; and the universal mounting of the bearing in the socket 12b will permit some rocking of the platform 12 on said bearing.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent is:

1. Pivot construction, including: upper and lower members, each carrying a bearing seat with an aperture therethrough; a pivot pin extending through said apertures; an upper nut on the upper end of the pivot pin having a bearing surface on its lower face engaging the bearing seat on the upper member; a locking member for the upper nut; a lower nut on the lower end of the pivot pin; and a locking member for the lower nut having a bearing surface on its upper face engaging the bearing seat on the lower member.

2. Pivot construction, including: upper and lower members, each carrying a concave bearing seat with an aperture therethrough; a pivot pin extending through said apertures; an upper nut on the upper end of the pivot pin having a convex bearing surface on its lower face engaging the bearing seat on the upper member; a locking member for the upper nut; a lower nut on the lower end of the pivot pin; and a locking member for the lower nut having a convex bearing surface on its upper face engaging the bearing seat on the lower member.

3. Construction as claimed in claim 1 in which the lower member has an upstanding sleeve surrounding the pivot pin and the upper member carries a bearing on said sleeve.

4. Construction as claimed in claim 1 in which the lower member has an upstanding sleeve surrounding the pivot pin and the upper member carries a bearing on said sleeve, said bearing being mounted on said upper member for universal movement with respect thereto.

JOHN W. PAGE.
